CONE WINDING MACHINE

Ethil Tonelli, Fall River, Mass., assignor to The Pairpoint Corporation, New Bedford, Mass., a corporation of Massachusetts

Application July 27, 1937, Serial No. 155,893

4 Claims. (Cl. 93—79)

This invention relates to an improvement in a cone winding machine and is a further development of the invention set forth in my Patent No. 1,765,779, dated June 24, 1930.

5 The present invention has for its primary object the formation upon a mandrel of a cone from a blank severed from a web by a series of operations taking place in timed relation to each other and at a desired relative speed.

10 A further object of this invention is the provision of a mandrel having a plurality of radially movable spurs by which the blank to be formed into a cone is held in place in combination with a presser plate and a plurality of brushes by

15 which the cone is formed.

Another object of this invention is the provision of a ring by which the finished cone is stripped from the mandrel, such ring being carried by the gripper unit which delivers the blank with which

20 the cone is to be formed.

Other objects of the invention reside in the structure and details of the various elements through which the results above mentioned are obtained, as will be apparent to one skilled in the art upon an examination of the following description and of the drawings which form a part thereof and in which—

Fig. 1 is a plan view of a machine embodying one form of this invention;

30 Fig. 2 is a side elevation thereof;

Fig. 3 is an enlarged cross-sectional view illustrating the winding and completing of the cone;

Fig. 4 is a side elevation of the mandrel on

35 which the cone is wound;

Fig. 5 is an enlarged longitudinal section of such mandrel; and

Figs. 6 and 7 are enlarged cross-sectional views thereof.

40 In the illustrated machine the cones are formed upon a mandrel from blanks cut from a web fed into the machine. Machines of this type are old and well known and in the following description those features common in the art which have been employed will be touched upon briefly and not discussed at length.

45 The web is fed from a roll (not shown) and after being saturated with a suitable adhesive by means well known in this art (such means being also not shown) is fed below a tension roll 10 which rests thereon over a rod 11 and between a pair of rollers 12. The rollers 12 are suitably mounted in a standard 13 upon the base 14 of the machine frame, which standard also supports the rod 11, and are yieldably held in contact with

each other by springs 19. The rollers are driven through suitable gearing from a common drive shaft 15 continuously rotated in one direction from a driven pulley 16 through a cross-shaft 17 and bevel gears 18. At one end of the lower roller 12 is fixed a gear 20 which meshes with a gear 21 carried by a suitably supported shaft 22 at the end of which is a pinion 23. The pinion 23 is mutilated having a flat surface 24 in a plane parallel to the axis of the shaft. Mounted on the main shaft 15 is a bevel gear 25 a portion of the teeth of which is omitted and replaced by a flat ring 26 adapted to rest against the flat surface 24 of the pinion. In Fig. 1 the flat surface 24 is shown in contact with the ring 26 so that the pinion, together with the gears and rollers, is at rest. As the bevel gear 25 is rotated the teeth thereon come into mesh with the teeth of the pinion and the rollers are driven. When one rotation of the shaft 22 has been completed the ring 26 again comes in contact with the flat surface 24 of the pinion and the parts are again at rest. It will be understood that the bevel gear 25 is provided with the same number of teeth as is the pinion 23.

25 As the web passes through the rollers 12 it rides upon a plurality of wires 30 the ends of which pass between the rollers, the latter having circumferential grooves 31 therein. The web then passes a cutter 32 having two arcuate blades 30 33 which converge outwardly, as shown in Fig. 1, to a severing and timing unit at which the leading end of the web is severed to provide the blank from which the cone is made, and the blank is trimmed. This includes a cutter 32 having two 35 arcuate blades 33 which converge outwardly, as shown in Fig. 1, and thus, as will be set forth below, give the desired form to the blank. The cutter 32 is supported at its wider end in bearings and is actuated by a bar 34 attached at the narrower end. The lower end of the bar 34 is secured to a stud shaft 35 rotatably carried in a bearing upon a bracket 36 mounted upon the base of the machine frame. The shaft 35 is provided with a gear 37 by which it is rotated and the end 40 of the bar is attached at the end of the shaft eccentrically of the axis so that as the shaft is rotated the cutter is raised and lowered. The shaft is driven intermittently through the gear 37 by a gear 38 on the main shaft 15. The gear 50 38 has teeth on part only of its circumference so that it meshes intermittently with the teeth of the gear 37. Carried by one face of the gear 38 is a plate 39 having an arcuate edge which registers with the untoothed portion of the gear 38. 55

Fixed to the corresponding face of the gear 37 is a plate 40 having a pocket which receives the edge of the plate 39. The plates 39 and 40 are so arranged that the gear 37 is held at rest until the 5 teeth thereof are meshed by the teeth of the gear 38 and a single complete rotation is imparted.

Carried by the base of the cutter are a pair of parallel fingers 41 on which the leading end of the web rests as it travels beyond the cutter. Simultaneously with the cutting operation the web is held in position on the fingers 41 by a curved plate 42. The plate 42 is carried by a rod 43 adjustably secured to one end of an arm 44 which is pivotally supported at its other end upon a bracket 45. Depending from the arm 44, intermediate its length, is a second arm 46 at the lower end of which is carried a roller 47. The roller is yieldably held in contact with the cutter 32 by a spring 48. The plate 42 is thus caused to move 10 in unison with the cutter and to clamp the web as the blank is severed therefrom.

The leading end of the web and subsequently the blank cut therefrom is further supported upon a plate 50 and a finger 51, both of which are 15 inclined downwardly as shown in Fig. 2. A notch 52 is provided at one side of the plate and the wall of the notch coacts with a blade 53 to sever a portion from one edge of the blank. The blade 53 is carried at the lower end of a post 54 secured 20 at its upper end in a slot at one end of a plate 55. The plate 55 is fixed at its other end to one end of a bar 56 pivotally supported at its other end upon a stud 57. The stud 57 projects from a sleeve 58 surrounding a post 59 secured at its 25 lower end in a bracket 60 fixed to the base of the frame. The bar 56 rests upon a cam 61 on the drive shaft 15 and is yieldably held in contact therewith. As shown in Fig. 2 a coil spring 62 on a stud 63 carried by the bracket 60 is connected by a compression spring 64 with the bar 56. Projecting from a sleeve 65 fixed to the post 59 above the sleeve 58 is a curved finger 66 connected by a spring 67 to the bar 56. Fixed to the plate 55 is a rod 68 having a spring pressed tip 69. The blade 53 is permitted by the rotation of the 30 cam to respond to the urge of the springs 62 and 64 and cut a portion from the edge of the blank. The tip 69 of the rod 68 knocks the cut-off portion away from the blank. The finger 66 and spring 67 act upon the bar 56 and cause the blade 53 to contact progressively with the wall of the 35 notch 52 as the bar descends.

The finger 51 is carried by one end of a bar 70 which bar is pivoted at its other end upon a stud 71 projecting from the upper end of a bracket 72 mounted upon the base 14 of the frame. A spring 73 attached to the bar 70 below the stud 71 yieldably holds the finger 51 in position.

The blank has now been severed from the web 40 and trimmed and is ready to be formed upon the mandrel 110 into a cone. The blank is advanced to the mandrel by a reciprocable gripper unit having a pair of jaws 75, 76 which seize the leading end of the web before the blank is severed and trimmed. As shown in Fig. 1 the jaws are at that time between the plate 50 and the finger 51 so that the web is securely held in the proper position for the severing and trimming operations.

The lower gripper jaw 75 is fixed upon a post 70 77 which is secured to an H-shaped block 78. The block 78 is mounted in a slot 79 in the base 14 of the machine and is reciprocated therein. A guide bar 80 secured to the base passes between the upper legs of the block and guides its movement. 75 As shown in Fig. 3, the post 77 is secured to the

upper legs of the block and forms therewith an enclosed aperture which receives the bar 80. Suitable bearing strips or shims 81 may be provided between the bar and the block. The upper gripper jaw 76 is pivoted intermediate its length upon a stud 761 carried by the post 77. Pins 82 and 83 project from opposite sides of the jaw. The pin 82 is near the tail thereof and the pin 83 about midway between the tail end and the stud. A spring 84 carried by the post and extending 10 under the pin 82 normally holds the upper jaw against the lower jaw and grips the blank therebetween.

The gripper unit is reciprocated by a cam 85 on the cross shaft 17 through a bar 86 pivoted 15 at its upper end upon a bracket 87 and connected at its lower end to the block 78 by a link rod 88. The link rod 88 is attached to the lower end of the bar through a sleeve 89 rotatable upon a stud 90 on the bar and is attached to the block 78 through 20 a sleeve 91 rotatable upon a rod carried by the lower legs of the block. A spring 92 attached at one end to the end of the link rod near the block and at the other end to a bracket 93 urges the gripper unit to move away from the severing and 25 trimming mechanism. A roller 95 on the bar 86 is held against the periphery of the cam 85 by the spring 92. The cam 85 includes a flange 96 defining a path 97 through which the roller 95 travels as the gripper unit is moved in one direction. 30

A bar 100 is pivoted intermediate its length upon the bracket 87. Projecting from one end of the bar is a stud 101 mounted for adjustment in a slot 102. The other end of the bar terminates over a cam 103 on the cross shaft 17 and is held against the periphery thereof by a spring 104. The cam 103 thus acts to oscillate the bar 100 for a purpose to be set forth below. Pivoted upon the post 77 is a latch 105 by which the gripper jaws are held open against the urge of the spring 84. The latch is a right angular member and carries on one arm a button 106 which when the jaws are open is advanced over the pin 83 by a spring 107 and thus prevents the closing of the 40 jaws. Mounted on the base is a bracket 108 carrying a roller 109 which is in the path of travel 45 of the other arm of the latch 105.

The gripper unit is shown in Fig. 2 at one limit of its movement with the jaws clamping a blank. 50 The cam 85 through the mechanism described above moves the gripper unit with the blank to its other limit of movement at which the blank is presented to the mandrel on which it is to be formed into a cone. As the unit reaches that 55 position the end of the upper gripper jaw 76 passes below the stud 101 which is thereupon lowered by the cam 103 to open the jaws and release the blank. The latch 105 thereupon holds the jaws open and the cam 85 returns the gripper 60 unit to its former position after the blank has been formed into a cone. As the unit reaches that position the roller 104 trips the latch and the jaws seize the leading end of the web prior to the severing and trimming operations.

The blank is formed upon a rotatable mandrel 110 the shaft of which is mounted in bearings on posts 111 and intermittently rotated from the drive shaft 15. The mandrel 110 is hollow (see Fig. 5) and carries a gear 112 secured thereto 70 between the bearings 111. Meshing with the gear 112 is a larger gear 113 fixed upon a stub shaft 114. The stub shaft is supported in bearings upon a bracket 115. A second gear 116 fixed upon the stub shaft 114 meshes intermittently with a muti- 75

lated gear 117 driven by the shaft 15. Secured to the faces of the gears 116 and 117 are plates 118 and 119 which correspond in structure and function to the plates 39 and 40 previously described and insure that the gear 116 is at rest except when the teeth of the gears 116 and 117 are actually in mesh. Mounted within the hollow of the mandrel is a partly tapered block 120 having a longitudinally extending slot 121 therein. Within the slot 121 are two bars 122 and 123. The bar 122 supports pin 124 which rest in slots 125 through the wall of the mandrel. The bar 123 is wedge-shaped and upon it rests the bar 122. Springs 126 yieldably hold the bar 122 against the bar 123. The springs 126 are each secured at one end to the bar 122 and at the other end to a cross pin 127 in a notch upon the block 120. The slot 121 is closed at one end by a plate 128 and at the other end by a plate 129 attached to the bar 122. From a consideration of this construction, as shown particularly in Fig. 5, it will be obvious that an advance of the bar 123 will cause the bar 122 to advance the pins 124 out of the slots 125 above the periphery of the mandrel so that they penetrate the blank and hold it stationary on the mandrel during the forming operation. The bar 123 is advanced and retracted by a rod 130 extending through the center of the mandrel shaft and connected by a link 131 to the upper end of an arm 132 pivoted at its lower end to a bracket 133 on the base. The tip of the arm is held yieldably against the periphery of a cam 134 on the cross shaft 17 by a spring 135. A spring 136 surrounds the rod 130 within the mandrel.

The blank delivered to the mandrel is held in contact therewith by a presser plate 140 carried by a plunger 141 pivoted upon a stud 142 projecting from an arm 143. The arm 143 is pivoted at its outer end upon a bracket 144 secured to the base and is actuated by a cam 145 on the drive shaft 15. The arm 143 is yieldably held against the cam 145 by a coil spring 146 supported by a bracket 147 depending from the frame base. The spring bears against a roller 148 carried by the yoke of an arm 149 fixed to and projecting downwardly from the arm 143 through a slot 150 in the base 14 (see Fig. 4). The presser plate 140 is yieldably held in register with the mandrel 110 by a spring 151. The arm 143 and cam 145 thus act to raise and lower the plunger plate. The raising action is supplemented by a beam 152 pivoted upon the bracket 147. One end of the beam extends below the arm 149 and is adapted to bear against a roller 153 carried thereby. The other end of the beam is connected by a link 154 and rod 155 with an arm 156 carried by a bracket 157. The arm 156 is raised and lowered by a cam 158 on the shaft 15 with the periphery of which it is yieldably held in contact by a coil spring 159 on the bracket 147. As suggested in dotted lines on Fig. 3, the cams 145 and 158 are so set that the arms 143 and 156 are simultaneously actuated to raise and lower the presser plate.

The blank is wiped around the rotating mandrel 110 by a brush 160 mounted upon a shaft 161 supported for rotation in a bearing carried by an arm 162. The arm 162 is rotatable upon a stub shaft 163 carried by a bracket 164. Secured to the arm 162 at the shaft 163 is a second arm 165 having a roller 166 which enters the enclosed path of a cam 167 driven by the shaft 15. Fixed on the brush shaft 161 is a gear 168 which meshes with a gear 169 carried by the arm 162

on a shaft provided also with a sprocket 170. The sprocket 170 is driven by a chain 171 from a sprocket 172 fixed on a collar 173 carried by the stub shaft 163. Fixed also to the collar 173 is a sprocket 174 driven by a chain 175 from a sprocket 176 on the shaft 15.

A second brush 180 is adjustably mounted upon an arm 181 fixed to a sleeve 182 surrounding a stud 183 carried by a post 184 mounted upon the frame base. Secured to the sleeve 182 is a second arm 185. The brush is yieldably urged toward the mandrel by a spring 186 carried by the post 184. Pivoted upon the post 184 is an arm 187 which projects at one side of the arm 185 and when swung on the pivot stud 188 causes the arm 185 to move the brush away from the mandrel. The arm 187 is actuated by a cam 189 on the cross shaft 17 through a stud 190 on an arm 191 pivoted on the bracket 192 and a link 193. A spring 194 connected at one end to the arm 191 and at the other end to a bracket 195 balances the spring 186 and holds the arms 185 and 187 in contact. An adjustable limit stop 196 on the bar 197 fixed to the post 184 determines the relation of the brush 180 to the mandrel.

After the cone has been formed on the mandrel 110 the ends may be trimmed by the blades 200 and 201. Each blade is carried by a right angled arm 202 fixed to a shaft 203 supported in bearings upon posts 204. Secured at one end of the shaft 203 is an arm 205 which carries a roller 206. The roller is adapted to rest against a cam 207 on the drive shaft 15 by which the blades are swung down against the mandrel to trim the ends of the cone and are then raised. Coil springs 208 carried by brackets 209 on the posts 204 act upon rods carried between tongues 210 on the arms 202 to hold the roller 206 in contact with the cam 207. In many instances the trimming of the cones is omitted and hence means are provided to hold the blades in an inoperative position. Such means are here shown as comprising an arm 211 fixed to the shaft 203 by which the roller 206 is raised out of the path of the cam 207. The arm 211 is locked in place by a latch bar 212 pivoted on a bracket 213 secured to a post 204 and having a notch which receives a stud 214 on the arm. In the drawings the blades 200 and 201 are shown locked in the inoperative position and the arms 205 and 211 integral.

The finished cones are stripped from the mandrel by a ring 215 fixed to a Z-shaped casting 216 mounted upon the post 17 of the gripper unit. After the gripper jaws have delivered the blank to the mandrel 110 the unit remains at rest until the cone has been completed and then starts its return. The ring 215 bearing against the larger end of the cone pushes the cone off the mandrel. As the cone leaves the mandrel it is struck by a knocker 217 and removed from the machine through the slot 150 in the base 14. The knocker 217 is secured to an arm 218 fixed to a stub shaft 219 carried in a bearing on the post 204. Secured to the shaft is a trip element 220 in the path of a cam 221 on the drive shaft 15. Upon each revolution of the shaft the knocker 217 is raised above the plane of the mandrel and then dropped carrying with it the cone stripped from the mandrel by the ring 215.

The operations of the various elements and units thus described take place in definite timed relation to each other. One cone is formed and ejected during each revolution of the main drive shaft 15. The elements are adjustable for cones

of different sizes. Since the drives to all the elements are from either the drive shaft 15 or the cross shaft 17 and since both these shafts are easily accessible the necessary adjustments 5 can be made easily and without interference with other parts of the machine.

I claim:

1. In a cone winding machine the combination of a web feeding mechanism, a severing and 10 trimming unit for severing a blank from the leading end of the web and trimming the blank, a gripper unit including gripper jaws by which the leading end of the web is clamped during the severing and trimming operation, a mandrel on 15 which the blank is formed into a cone, means for causing said gripper jaws to present the finished blank to the mandrel, a presser plate for holding the blank to the mandrel, means for securing the blank in position on the mandrel, 20 means for rotating the mandrel and blank, brush means for wiping the blank about the mandrel as it is rotated, and means for stripping the formed cone from the mandrel.
2. In a cone winding machine the combination of a web feeding mechanism, a severing and trimming unit for severing a blank from the leading 25 end of the web and trimming the blank, a gripper unit including gripper jaws by which the leading end of the web is clamped during the severing and trimming operation, a mandrel on which the blank is formed into a cone, means for causing 30 said gripper jaws to present the finished blank to the mandrel, a presser plate for holding the blank to the mandrel, means for securing the blank in position on the mandrel, means for rotating the mandrel and blank, brush means for 35

wiping the blank about the mandrel as it is rotated, and means for stripping the formed cone from the mandrel, said means including a ring carried by the gripper unit and passed over the mandrel as the blank is presented thereto and as the unit returns to obtain another blank after the cone has been completed. 5

3. In a cone winding machine, a hollow mandrel on which the cone is formed from a blank, a plate within said mandrel, spurs on said plate 10 riding in slots in the wall of the mandrel, and means for causing said plate to advance the spurs in the slots so that they project beyond the periphery of the mandrel and engage the blank thereon, such means including a tapered 15 block having a longitudinally extending slot therein and which receives said plate, a wedge-shaped plate in said slot between the spur-supporting plate and the base of said slot, and means for advancing said wedge-shaped plate to move 20 the spur-supporting plate radially.

4. In a cone winding machine, a mandrel on which a blank is wound into a cone, a source of such blanks, a gripper reciprocable on a line parallel to the longitudinal axis of the mandrel, 25 means for so actuating said gripper that, as it travels in one direction, it seizes a blank and, as it travels in the other direction, it presents that blank to the mandrel, and a ring carried by said gripper and reciprocable thereby over the 30 mandrel, which ring, as the gripper travels in the first-named direction, engages and strips from the mandrel the cone wound thereon from the blank presented thereto.

ETHIL TONELLI.

35
